UNITED STATES PATENT OFFICE.

ELI MONDEN, OF RAWLINS, WYOMING.

SACK-HOLDER.

SPECIFICATION forming part of Letters Patent No. 634,760, dated October 10, 1899.

Application filed June 5, 1899. Serial No. 719,441. (No model.)

To all whom it may concern:

Be it known that I, ELI MONDEN, of Rawlins, in the county of Carbon and State of Wyoming, have invented a new and Improved 5 Sack-Holder, of which the following is a full, clear, and exact description.

This invention relates to improvements in devices for holding sacks when receiving ore, grain, or any other material designed to be 10 placed in sacks; and the object is to provide a sack-holder of simple and comparatively inexpensive construction with which sacks may be quickly engaged and from which the filled sacks may be easily removed.

15 I will describe a sack-holder embodying my invention and then point out the novel features in the appended claims.

Reference is to be had to the accompanying drawings, forming a part of this specification, 20 in which similar characters of reference indicate corresponding parts in all the figures.

Figure 1 is a front elevation and partial section of a sack-holder embodying my invention. Fig. 2 is a side elevation of the same. 25 Fig. 3 is a top view of the same. Fig. 4 is a section on the line 4-4 of Fig. 1. Fig. 5 shows one of the supporting-bars employed, and Fig. 6 shows a construction that may be employed for supporting sacks or bags other than 30 ore-sacks.

The sack-holder comprises a frame consisting of the front uprights 1, the rear uprights 2, the top bars 3, and the lower brace-bars 4. This frame is open at its front, so that a sack 35 when filled may be removed through said opening.

Mounted to swing on the frame are sack-supporting bars 5 6. These sack-supporting bars have hinge connections 7 with one of the 40 top brace-bars, and these hinge connections are so arranged that the sack-supporting bars may be spread apart or elevated relatively to the frame when it is desired to release the sack.

45 Having swinging connection with one of the sack-supporting bars is a hopper 8, and upon the upper side of each sack-supporting bar is a block 9, having recesses 10 at its ends to receive cross-bars 11, that are usually secured 50 to the ends of ore-sacks. I also provide a

block 12, upon which the lower end of a sack may rest, and this block permits the contents of the sack to be shaken down or packed closely and without undue strain on the upper portion of the sack. 55

When the device is to be used for supporting sacks other than ore-sacks or sacks for containing grain, potatoes, or the like and which are not provided with cross-bars 11, I provide opposite top bars of the frame with 60 hooks 13, with which the sack may be engaged.

In operation the hopper 8 is to be swung back, substantially as shown in dotted lines in Fig. 2, and then the sack-supporting bar 5 may be swung outward to allow a sack to be 65 placed in the frame, so that after again swinging the bar 5 inward the cross-bars 11, attached to the sack, will rest on said sack-supporting bars in the recesses 10. The shoulders of these recesses 10 will prevent the cross-bars 11 from moving toward each other. After moving the hopper downward, as indicated in full lines in the drawings, the material to be sacked is to be shoveled into said hopper, 70 from which it will flow into the sack. When 75 filled, the hopper must again be raised and the sack-supporting bars be spread apart or elevated to release the sack.

Having thus fully described my invention, I claim as new and desire to secure by Letters 80 Patent—

1. A sack-holder, comprising a frame open at one side, sack-supporting bars mounted to swing both laterally and vertically on said frame, and a hopper having swinging connection with one of the bars, substantially as 85 specified.

2. A sack-holder, comprising a frame, sack-supporting bars mounted to swing laterally and vertically on the frame, blocks on the upper sides of said bars and having recesses at the ends to receive cross-bars attached to the sack, and a hopper having swinging connection with one of the sack-supporting bars, substantially as specified. 90

ELI MONDEN.
